(No Model.)

H. MASSICKS & W. CROOKE.

HOT BLAST STOVE.

No. 398,840.

Patented Mar. 5, 1889.

UNITED STATES PATENT OFFICE.

HORACE MASSICKS AND WALTER CROOKE, OF THE PARISH OF MILLOM,
COUNTY OF CUMBERLAND, ENGLAND, ASSIGNEES TO GEORGE W.
McCLURE AND LOUISA SCHULER, EXECUTRIX, BOTH OF PITTSBURG,
PENNSYLVANIA.

HOT-BLAST STOVE.

SPECIFICATION forming part of Letters Patent No. 398,840, dated March 5, 1889.

Application filed October 29, 1886. Serial No. 217,538. (No model.) Patented in England March 24, 1881, No. 1,312.

To all whom it may concern:

Be it known that we, HORACE MASSICKS and WALTER CROOKE, both of the parish of Millom, in the county of Cumberland, England, have invented a new and useful Improvement 5 in Hot-Blast Stoves, (patented to us in England on March 24, 1881, No. 1,312,) and we do hereby declare the following to be a full, clear, and exact description thereof, reference being had to the accompanying drawings, forming a part of this specification, in which—

Figure 1 is a vertical section of a hot-blast stove constructed according to the principles of our invention. Fig. 2 is a horizontal cross-section on the line $x-x$ of Fig. 1.

Like symbols of reference indicate like parts in each.

In the drawings, a represents the hollow cylindrical shell of a hot-blast stove. Within 10 it is divided by vertical concentric walls or divisions a' a^2 a^3 , which are preferably divided segmentally by vertical radial walls or divisions B , extending from the middle of the stove to the wall a . The wall a' , which is a 15 small partition-wall, extends from the bottom nearly to the top of the stove, the wall a^2 extends from top to bottom, and the wall a^3 extends from the bottom nearly to the top. The wall a^3 would form a cylindrical chamber in 20 the center of the stove, but the radial walls B divide it into segments for the greater part of its length. By means of these walls the stove is divided into three sets of vertical flues—the flues b b' , which are practically 25 one flue, the flue c , and the flues d d' —which together form one flue and unite at their bases, opening into the vertical flue E' , which, through an arched horizontal branch, E , leads to the hot-blast main B' and to the gas-main 30 A' . At the top of the division-wall a^3 the flues d , d' , and c open into a common dome or chamber, e , which connects them. The flues b b' are connected at the top of the stove by a horizontal arched flue, f , and from this flue 35 branch flues g lead to the discharge or stack flue h , which is at the top of the stove.

i is the cold-blast supply-pipe, which enters the flues g at the base of the stack-flue h .

D is a valve controlling the pipe i , and h'

is a valve controlling the flue h , by operation 50 of which either of the flues h or i may be cut off from communication with the flues g and communication of the other therewith established. The vertical flues b b' communicate with each other at their bases through short 55 arched flues k , and also communicate with the flues c through horizontal arched flues m .

n is the usual hot-air valve, A is the gas-valve, and p is a flue through which air is admitted to support combustion in the flue E . 60

The operation is as follows: To heat the flues of the stove, the valve D of the cold-air pipe i and the valve n of the hot-blast pipe B' are closed and the gas-valve A and the valve h' of the discharge-flue h are opened. The 65 gas will then enter the flue E and ignite, and thence will traverse the uptake-flues d d' , chamber e , flues c , flues m , and thence up through flues b b' and flues g to the discharge-stack h . When the walls have been heated 70 sufficiently, the valves h' and A are closed and the valves D and n opened. The cold blast will then pass downward from pipe i through flues g and b b' , thence up through the flues c into chamber e , and downward 75 through flues d d' into flue E , and thence through the hot-blast main B' to the furnace.

The principal feature of our invention as thus described is the location of the discharge-flue h and the cold-blast inlet at the top of the 80 stove, in connection with the first or main combustion-flues located at the center or middle portion of the stove, and the use of an odd number of sets of flues or passes, b b' , c , and d d' , whereby we are enabled to have this arrangement. The advantage of this position of the flue h and flues d d' is that it avoids the necessity for the use of large independent stack; and at the same time the main and first heat is communicated to the middle portion 90 of the stove, whereby loss of heat by radiation is avoided, and also greater facilities are offered in cleaning the stove from foreign deposits.

By reason of its little cost, our improved 95 stove is of great advantage for use with small furnaces and as an auxiliary stove for large furnaces, where it is not desirable to construct

a large stack and where the stacks already in use have not sufficient capacity to accommodate an additional stove.

We do not limit ourselves to the precise arrangement of the flues which we have shown and described; nor do we desire to claim, broadly, what is known as a "three-way hot-blast stove," as the same is shown and described in certain foreign Letters Patent granted for inventions made by Camille Leveque, among which are British Letters Patent No. 3,376, dated October 18, 1873; but

What we claim as our invention is—

1. A vertical hot-blast stove constructed with a gas-inlet leading to an uptake flue or flues arranged centrally of the stove, a suitable number of downtake flues outside of the central flue, and a final uptake flue or flues outside of the downtake flues, a chimney-flue leading therefrom at the top of the stove, and valves at the gas-inlet and at the chimney adapted to control the flow of air

and gas to and from the stove, substantially as described.

2. A vertical hot-blast stove having wall-work arranged to form an odd number of passes, a discharge-flue with which the upper passes are connected, a cold-blast inlet at the top of the stove, an uptake flue or flues arranged centrally of the stove and provided with a gas-inlet and constituting the first pass, a hot-blast outlet at the base of the stove, and valves arranged in conjunction with the air-blast, gas-inlet, and hot-blast outlet, substantially as described.

In testimony whereof we have hereunto set our hands this 6th day of October, A. D. 1886.

HORACE MASSICKS.
WALTER CROOKE.
